UNITED STATES PATENT OFFICE.

CHARLES D. GRAFF, OF NEW YORK, N. Y., ASSIGNOR TO REDLICH & CO.,
OF SAME PLACE.

DESIGN FOR A BACK FOR BRUSHES OR SIMILAR ARTICLES.

SPECIFICATION forming part of Design No. 26,216, dated October 27, 1896.

Application filed September 11, 1896. Serial No. 605,540. Term of patent 3½ years.

To all whom it may concern:

Be it known that I, CHARLES D. GRAFF, of New York, in the county and State of New York, have invented and produced a new and original Design for the Backs of Brushes or Similar Articles, of which the following is a full, clear, and exact specification.

Reference is to be had to the accompanying drawing, forming a part of this specification, in which the figure is a plan view of a back for brushes, showing my design.

The leading feature of my design consists of a raised garland of flowers A, surrounded by a roccoco border B in relief, with plain

raised surfaces C between the border and the 15 garland.

A minor feature of the design consists in the extension of the roccoco border B along the handle portion of the article, and in the lower end of the border is a rose-like figure D. 20

I claim—

The design for a back for brushes or similar articles, as herein shown and described.

CHARLES D. GRAFF.
